SCRAP CUTTER

Frederick M. Littell, Detroit, Mich., assignor to
 F. J. Littell Machine Company, Chicago, Ill., a
 corporation of Illinois

Application February 13, 1943, Serial No. 475,747

8 Claims. (Cl. 164—10.6)

The invention relates to scrap cutters and has reference more particularly to apparatus for attachment to a punch press and which may be actuated continuously, that is, on each operation of the press, or intermittently, in which case a variable number of press operations intervene, for cutting the material into any length desired. In stamping operations and in many other operations, such as are performed on a punch press, the material is taken from a coil and presented to straightening rolls where the same is straightened and then fed under the die or punch of the press. The perforated material resulting from said operation is generally fed to a scrap cutter for cutting the material into suitable lengths. The present invention has for a primary object the provision of a scrap cutter of relatively simple construction and which may be rendered operative by merely rotating an eccentric to locate the same in its lowermost position.

A further object is to provide a reciprocating type of scrap cutter having an oscillating fulcrum member and wherein a cutting operation is effected by rotating an eccentric to thereby lower the fulcrum point of said member to render the cutting knives operative.

A further object is to provide an intermittent scrap cutter having a rotatable eccentric for controlling actuations of the scrap cutter and which eccentric may be rotated from one position to the other by manual actuation or by power means electrically controlled.

A further object is to provide an intermittent scrap cutter including an oscillatable member and rotatable eccentric means for effecting a cutting operation and wherein said eccentric means must be positioned on lower dead center or beyond to provide the necessary lock for holding the pivot end of the fulcrum member against the tension of the cutting knives.

With these and various other objects in view, the invention may consist of certain novel features of construction and operation as will be more fully described and particularly pointed out in the specification, drawings and claims appended hereto.

In the drawings, which illustrate an embodiment of the invention, and wherein like reference characters are used to designate like parts—

Figure 1 is a side elevational view showing the scrap cutter of the invention equipped with pressure means for rendering the same operative in timed relation with the press;

Figure 2 is a front elevational view of the scrap cutter of Figure 1 more clearly illustrating the

electrical means for controlling the pressure cylinder whereby the scrap cutter is rendered operative;

Figure 3 is a part elevational and part sectional view illustrating the position of the eccentric when the cutting knives are operative;

Figure 4 is a side elevational view showing a modification of the invention wherein a handle is substituted for the pressure means; and

Figure 5 is a front elevational view of the modified form of Figure 4.

Referring to the drawings, particularly Figure 1, the scrap cutter of the invention is shown in connection with the operating instrumentalities of a punch press or the like with which the scrap cutter may be associated. The press has a main operating shaft indicated by numeral 10 which drives the scrap cutter and also the timing mechanism for controlling actuation of said cutter.

20 The cam 11 on the main operating shaft has connection at 12 with a connecting link 14 joined at its lower end as at 15 to a clevis 16. The clevis in turn has a releasable connection with an oscillating member 18. The pivot pin 20 joins the clevis 16 to the member 18 but the pin is removable in order that the point of connection may be varied since the openings 21 and 22, for example, may also be utilized for this purpose.

25 The oscillating member 18 has pivotal movement about a fulcrum point 24, located at the end of the member opposite pin 20. Therefore this bifurcated end of member 18 is fulcrummed by pin 24 and oscillating movement is imparted to the opposite end through clevis 16, connecting link 14 and cam 11. The pivot pin 25 is located intermediate the ends of the member and this pin pivotally connects to said oscillating member the depending arms 26 which in turn carry at their lower end the movable cutting knife 27.

30 The scrap material to be cut by apparatus of the invention is suitably fed between the movable cutting knife 27 and the stationary knife 28, the same being fixed to the base structure indicated in its entirety by numeral 30. Said base structure provides a support 31 which primarily functions to support the scrap material and direct the same toward the cutting knives 27 and 28. The base structure also provides upwardly directed bosses 32 to which are fixed the upright posts 33.

35 Each depending arm 26 has formed integral therewith a tubular guide portion 34 and the same is mounted on one of the posts 33 to thereby guide the arms in their vertical reciprocating movement. As a result of this structure the cutting knife 27, which extends transversely between

the arms 26, being fixed thereto, is caused to move in a vertical plane properly aligned with respect to the stationary knife, which likewise extends transversely, being located to the rear of the support 31. The movement imparted to said knife 27 is due to the oscillating movement of member 18, pivotally fulcrummed at its bifurcated forward end by means of pin 24.

The pin 24 in addition to fulcrumming the oscillating member 18 is adapted to have bodily movement in a substantially vertical plane, which movement serves to control the cutting operations. The position of the fulcrum pin 24 determines the position of cutting knife 27 with respect to the stationary knife 28. With pin 24 in its uppermost position the knife 27 does not contact the stationary knife 28 even during the lowermost point of oscillating movement of member 18. Therefore with pin 24 located as shown in Figure 1 cutting operations do not take place even though the knife 27 reciprocates in a vertical plane to and from the stationary knife 28. It will be clearly understood that when the pivot pin 24 is lowered to an extent where the cutting knives will contact that the desired cutting operation will be caused to take place, since if scrap material is between the knives at this moment the same will be severed. The invention provides eccentric means for adjusting the position of the pivot pin 24, which structure will now be described.

The base structure 30 provides spaced uprights 35, as clearly shown in Figure 2. A boss 36 is formed on each of the spaced uprights and it will be understood that said bosses are in horizontal alignment for journaling the pivot portions 37 of the eccentric 38. The eccentric is connected by a link with the pivot pin 24. Said link includes a bearing portion 40 pivotally mounted on pin 24 and a somewhat similar bearing portion 41 having pivotal mounting on the eccentric. The threaded stud 42 joins the bearing portions 40 and 41 to complete the link and said stud is adjustable so that the desired spacing between pivot pin 24 and the eccentric 38 can be secured.

The eccentric is shown in Figures 1 and 2 in its elevated position. In this position, it will be clearly seen that the pivot pin 24 has been elevated sufficiently so that the movable cutting knife 27 does not coat with knife 28. In this elevated position of the eccentric the cutting knives do not perform a cutting operation, notwithstanding that knife 27 has vertical reciprocating movement as a result of the oscillating movement of member 18. To effect a cutting operation the eccentric must be rotated substantially 180 degrees from its position as shown in Figures 1 and 2. In other words, the eccentric must be moved from an elevated position where the cutting knives are inoperative to its lowermost position whereby the apparatus is rendered operative as shown by Figure 3. In this lowermost position of the eccentric the same can be considered as on lower dead center. In fact, it is necessary for the eccentric to be located on lower dead center or beyond in order to provide the necessary lock holding the fulcrum end 24 of the oscillating member against the tension resulting from the cutting operation. The action of the cutting knife 27 is in a downward direction for cutting the scrap material. Enormous tension is therefore applied to the pivot pin 24 which is equal and opposite to that of the movable knife 27. The tendency of the pin therefore is to move upwardly and it must be securely locked in its lower operative position. By rotating the eccentric so that the same is on

lower dead center or slightly beyond a secure lock is provided which effectively prevents upward movement of pin 24 until the eccentric is purposely rotated to accomplish this result.

Figures 1 and 2 illustrate a preferred form of power means for rotating the eccentric. Said power means consists of a pressure cylinder 44 having a piston 45. The piston carries a rack 46 which has vertical reciprocating movement in suitable guiding means 47. The rack has meshing relation with a pinion 48 on the left pivot portion 37 of the eccentric 38, as clearly evident from Figure 2. The pressure cylinder 44 has connection with suitable piping 50 and 51 for conducting a pressure fluid to the cylinder and for carrying said fluid away from the cylinder.

The reference numeral 52 indicates a solenoid operated valve control, the same including a solenoid 53, armature 54 and valve control chamber 55. The pipes or conduits 50 and 51 connect with the control chamber 55. Said chamber is also provided with an inlet 56 and with an exhaust 57. The structure operates to control the admission of pressure fluid to the cylinder 44 and the exhaust of the fluid therefrom.

When it is desired to move the rack 46 in a downward direction to rotate the eccentric 38 pressure fluid is admitted by control 52 to conduit 51 to cause downward movement of the piston within cylinder 44. Simultaneously with the admission of fluid to conduit 51 the fluid within the cylinder is permitted to exhaust through conduit 50. This action of the control valve will rotate the eccentric to render the scrap cutter operative. When it is desired to elevate the eccentric to render the cutting instrumentalities thereof inoperative the action of the valve control means is reversed and pressure fluid is admitted to conduit 50 and allowed to exhaust through 51.

The solenoid 53 is energized by any suitable source of alternating current supplied to conductors L₁ and L₂. The micro-switch 58 is connected in series with the solenoid 53 and tripping of the micro-switch therefore controls the energization of said solenoid and corresponding actuation of the valve control means. The micro-switch 58 is suitably located within housing 59 which is adjustably supported on the side of the press by the bracket 60. The housing 59 provides mechanism for actuating the micro-switch which includes the ratchet 61 and pawl 62, the latter having the cam roller 63 at the outer end thereof. The cam roller is suitably maintained in contact with cam 64 on shaft 10 of the press and periodically the cam roller is caused to engage cam portion 65 of said cam to produce actuation of pawl 62. The ratchet 61 is therefore indexed one notch for each complete rotation of the main operating shaft 10 of the press. In the form as shown in Figure 2 the micro-switch is actuated at intervals, depending on the number of pins 66 carried by the ratchet wheel 61. These pins contact an arm 67 located within the housing 59 and as a result of downward movement of said arm the micro-switch 58 is actuated.

Figures 4 and 5 show a modification of the invention wherein a handle is substituted for the pressure means. It will be understood that the oscillating member 118 has connection with the main operating shaft of the press through the same linkage as disclosed with respect to Figures 1 and 2. Said member has pivotal movement about the fulcrum point 124 and by means of pin 125 the depending arms 126 are reciprocated to cause vertical movement of knife 127 with re-

spect to knife 128. Spaced uprights 135 are provided by the base structure and the journalling bosses 136 formed thereon are in horizontal alignment for journalling the eccentric 138. The pin 124 and eccentric 138 are suitably connected by the linkage including the bearing portions 140 and 141 and the threaded stud 142. In Figures 4 and 5 the eccentric is shown in an operative lower position, the same having been rotated into this position by means of a handle 170 having the handle portion 171. The handle is non-rotatably fixed to the right hand journalling portion 137 of the eccentric 138. A stop member 172 is also similarly fixed to this journalling portion 137 and said stop member is adapted to coact with the stop 173 whereby the operative and inoperative positions of the handle are indicated. Although not absolutely necessary the bearing portion 141 may provide the spring pressed detent 174 by means of which the eccentric is held in an operative position.

The scrap cutter of the invention is relatively simple in construction and can be easily rendered operative or inoperative. At all times the oscillating member 18 fulcrums on pin 24 and the knife 27 has movement in a vertical plane for each oscillation of said member. The cutting knives are rendered operative merely by lowering the fulcrum point 24 or 124 in the modification of Figures 4 and 5. The eccentric 38 provides the means whereby the position of the fulcrum point may be controlled. This structure has the advantage that when located in lower dead center position or beyond the same provides a lock effectively preventing inadvertent upward movement of the linkage including the threaded stud 42 and of course the pivot pin 24. Whereas, the eccentric must be positioned in lower dead center position or beyond to render the cutting knives operative, it is not necessary that the eccentric be moved a complete 180 degrees for an inoperative position. A 90 degree rotation of the eccentric from its lower dead center position would in many cases be sufficient to prevent the cutting knives from coacting. However, for safety purposes and in order that fairly thick scrap material may be cut the invention discloses the eccentric as in upper dead center position when inoperative.

The invention is not to be limited to or by details of construction of the particular embodiment thereof illustrated by the drawings, as various other forms of the device will of course be apparent to those skilled in the art without departing from the spirit of the invention or the scope of the claims.

What is claimed is:

1. In apparatus of the character described, a reciprocable cutting slide, an oscillating member pivotally connected to the cutting slide for reciprocating the same, means providing a fulcrum for the oscillating member, and an eccentrically journalled shaft operatively associated with said fulcrum means for adjusting the position of said means, whereby to render the cutting slide operative or inoperative.

2. In apparatus of the character described, a base providing a stationary blade, a cutting slide mounted for movement to and from said stationary blade for coaction therewith, an oscillating member pivotally connected to the cutting slide for reciprocating the same, means providing a fulcrum for the oscillating member, and an eccentrically journalled shaft operatively associated

with said fulcrum means for adjusting the position of said means, whereby to render the cutting slide operative or inoperative with respect to the stationary blade.

3. In apparatus of the character described, a base providing a stationary blade, a cutting slide mounted by said base so as to have reciprocating movement toward and from the stationary blade, an oscillating member pivotally connected to the cutting slide for reciprocating the same, means providing a fulcrum for the oscillating member including a pivot pin, a shaft eccentrically journalled by said base, and means operatively connecting said eccentric shaft and said pivot pin, whereby rotation of the eccentric shaft will move the pivot pin bodily with respect to the base to render the cutting slide operative or inoperative.

4. In cutting apparatus of the non-flying type, a base providing immovable, spaced upstanding posts and said base supporting a stationary blade between said posts, a slide supported by said posts for reciprocation, said slide carrying a cutting blade for coaction with the stationary blade, an oscillating member pivotally connected to said slide and operating to reciprocate the slide upon oscillating movement of the member, means providing a fulcrum for one end of said oscillating member including a pivot pin, an eccentric journalled by said base for rotation and operatively connected to said pivot pin, whereby rotation of the eccentric will change the position of the pivot pin bodily with respect to the base to render the cutting blade operative or inoperative with respect to the stationary blade.

5. In cutting apparatus of the non-flying type, a base having immovable, spaced uprights providing journalling means, an eccentric rotatably mounted by said journalling means and extending between the same, a link member having one end thereof mounted on the eccentric and journalling a pivot pin at its opposite end, an oscillating member pivotally connected to said link member by means of said pivot pin which thereby provides a fulcrum for the oscillating member, a reciprocable cutting slide supported by the base for coaction with respect to a stationary blade fixed to the base to perform a cutting operation, said slide having pivotal connection with the oscillating member whereby oscillation of the same reciprocates said slide, and means for rotating the eccentric to cause bodily movement of the pivot pin with respect to the stationary blade to render said cutting slide operative or inoperative.

6. In cutting apparatus of the non-flying type, a base having immovable, spaced uprights providing journalling means, an eccentric rotatably mounted by said journalling means and extending between the same, a link member having one end thereof mounted on the eccentric and journalling a pivot pin at its opposite end, an oscillating member pivotally connected to said link member by means of said pivot pin which thereby provides a fulcrum for the oscillating member, spaced upstanding posts fixed to the base, a stationary blade located between the posts, a reciprocable cutting slide mounted by said posts and having movement toward and from the stationary blade to coact therewith, means pivotally connecting the cutting slide with the oscillating member whereby movement of the member reciprocates the slide, and means for rotating the eccentric to cause bodily movement of the pivot pin with respect to the stationary blade to render the cutting slide operative or inoperative.

7. In cutting apparatus of the non-flying type, base structure providing a fixed, stationary cutting blade, a cutting slide mounted for movement on said base structure in a direction toward and from the stationary blade to coact therewith in performing a cutting operation, a member fulcrumed at one end and pivotally connected to the cutting slide intermediate its ends for reciprocating the slide upon oscillating movement of the member, an eccentric journalled for rotation by means fixed to the base structure, a connecting link mounted on the eccentric at one end and providing a pivot pin at its opposite end, said pivot pin connecting the member to the link and forming the said fulcrum of the member, whereby the pivot pin is bodily movable to and from the base structure upon rotation of the eccentric to render the cutting slide operative or inoperative to perform a cutting operation, and means connected to the member at its end opposite the fulcrum for oscillating the same.

8. In cutting apparatus of the non-flying type, base structure providing a fixed, stationary cutting blade, a vertically movable cutting slide adapted to coact with the blade in performing a cutting operation, an oscillating member pivotally connected to the slide for reciprocating the same, an eccentric journalled for rotation on a horizontal axis by the base structure, a substantially vertically disposed link having one end 10 operatively mounted on the eccentric and having its other end pivotally connected to the oscillating member to provide a fulcrum for the same, whereby the cutting slide is operative to perform a cutting operation when the eccentric is located in its lower dead center position and whereby the cutting slide is rendered inoperative by rotation of the eccentric to locate the same substantially in its upper dead center position.
